UNITED STATES PATENT OFFICE.

HERBERT E. WHITE, OF YOUNGSTOWN, OHIO, ASSIGNOR TO THE GENERAL FIRE-PROOFING COMPANY, OF YOUNGSTOWN, OHIO, A CORPORATION OF OHIO.

PAINT-SPRAYING DEVICE.

1,162,717.

Specification of Letters Patent. Patented Nov. 30, 1915.

Application filed December 9, 1912. Serial No. 735,681.

To all whom it may concern:

Be it known that I, HERBERT E. WHITE, a citizen of the United States, residing at Youngstown, in the county of Mahoning and State of Ohio, have invented certain new and useful Improvements in Paint-Spraying Devices, of which the following is a specification.

The present invention relates to a device for applying some coating medium such as paint to expanded metal, metal lath, or similar perforate material, the object of the invention being to provide a coating mechanism of this character which embodies novel features of construction whereby the paint or coating medium can be quickly and effectively applied to both sides of the expanded metal without excessive waste of the paint.

It has been found impractical to use the ordinary spraying devices for painting expanded metal or similar perforate articles, owing to the fact that much of the paint or coating medium passes through the perforations and is wasted, and among the objects of the present invention is to provide a device in which this objection is overcome by oppositely disposed nozzles which are arranged upon opposite sides of the member to be coated and produce jets which meet in substantially the plane of the said member so as to produce a veritable atmosphere of the coating medium.

A further object of the invention is to provide a spraying or coating device which is comparatively simple and inexpensive in its construction, which is continuous in its operation, and which admits of the nozzles being readily adjusted so as to always obtain the best results.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in

50 which:—

Figure 1 is a top plan view of a paint spraying device constructed in accordance with the invention, portions being broken away. Fig. 2 is a side elevation of the same,

portions being broken away and shown in 55 section, and Fig. 3 is a transverse vertical sectional view through the device.

Corresponding and like parts are referred to in the following description and indicated in all the views of the drawings by the same 60 reference characters.

Specifically describing the present embodiment of the invention, the reference character A designates an endless conveyer which may be of any suitable construction 65 and upon which the expanded metal members 1 are placed. This conveyer A is shown as comprising the two chains 2 which are connected by the transverse supporting rods 3 and pass around the sprockets 4 upon the 70 shaft 5. Power may be applied to the shaft 5 in any suitable manner for the purpose of driving the conveyer and carrying the expanded metal members 1 thereon between the opposed upper spraying nozzles 6 and 75 lower spraying nozzles 7.

The upper and lower spraying nozzles 6 and 7 are carried by a frame B through which the upper reach of the endless conveyer A passes. This nozzle carrying frame 80 B is substantially rectangular in shape and is formed with tubular end pieces 8 and 9, the middle portion of the end piece 8 communicating with and being swiveled at 10 to a main air supply pipe 11, while in a 85 similar manner the middle portion of the tubular end piece 9 communicates with and is swiveled at 12 to a main paint supply pipe 13. These two swiveled joints 10 and 12 have an opposed relation and are in alignment with each other so that the nozzle carrying frame B can be swung about a substantially horizontal axis or an axis in the plane of the member being coated.

The top and bottom of the nozzle carrying frame B each comprise a pair of tubular members 14 and 15 which are arranged side by side, the member 14 communicating with the tubular end piece 9, while the member 15 communicates with the tubular end piece 8. Each of the spraying nozzles is supported between a pair of tubular arms 16 and 17, the arm 16 communicating with the member 14 while the arm 17 communicates with the member 15. With this construction it will be obvious that the tubular arms 16 will serve to supply paint to the nozzles, while the tubular

arm 17 will serve to supply compressed air to the nozzles, the passage of compressed air through the nozzles acting in the usual manner to produce suction and eject the paint in the form of a spray.

The varicus nozzles 6 and 7 are pivotally mounted between the arms 16 and 17 so as to turn freely about a horizontal axis or an axis parallel to the member 1 being coated.

10 This admits of the upper and lower nozzles 7 and 8 respectively being adjusted upon the nozzle carrying frame B so as to operate in the most effective manner upon the expanded metal or metal lath. As has been 15 previously explained, the nozzle carrying frame B can also be tilted as may be required. In Fig. 2, the nozzle carrying frame B is shown by full lines in an upright or vertical position, and by dotted lines as tilted into an inclined position.

20 This same figure of the drawing also serves to illustrate the manner in which the nozzles can be adjusted with respect to the frame B, the said nozzles being shown by full lines 25 as tilted into positions at an angle or inclination to the plane of the frame B, so that the jets therefrom meet each other at an angle, and by dotted lines as swung into a directly opposed relation.

30 The jets of paint or coating material from the upper and lower opposed nozzles 6 and 7 meet substantially in the plane of the expanded metal member 1 so as to produce a veritable atmosphere of the coating material, through which the said expanded metal member is moved by the conveyer. Both sides of the expanded metal member are thus effectively coated, and owing to the opposed relation of the nozzles and the meeting of 35 40 the jets in the plane of the member, the usual and objectionable waste of the coating material or paint is avoided.

Having thus described the invention, what I claim as new and desire to secure by Letters Patent, is:

1. A device for coating expanded metal and the like, including oppositely disposed spraying nozzles arranged on opposite sides of the member to be coated so that the jets 50 55 therefrom meet substantially in the plane of the said member, and a pivotally mounted supporting frame carrying the nozzles, the said frame being adapted to be tilted to swing the nozzles toward or away from the member being coated.

2. A device for coating expanded metal and the like, including oppositely disposed and adjustably mounted spraying nozzles arranged on opposite sides of the member to 60 65 be coated so that the jets therefrom meet substantially in the plane of the said member, and a pivotally mounted supporting frame carrying the nozzles, the said supporting frame being adapted to be tilted about its axis to swing the nozzles toward or away

from the member being coated and the nozzles themselves being adjustable so that the inclination thereof with respect to the frame can be varied.

3. A device for coating expanded metal and the like, including conveying means for the member to be coated, a swinging frame mounted to turn about an axis substantially in the path of the said member, and oppositely disposed nozzles adjustably mounted upon the swinging frame and arranged on opposite sides of the path of the member so as to be moved toward and away from the same as the frame is swung about its axis, the jets from the nozzles meeting in the path of the member so as to produce an atmosphere of the coating material through which the member is conveyed, and the inclination of the nozzles with respect to the frame being adjustable as desired.

4. A device for coating expanded metal and the like, including a frame formed with tubular end pieces connected by opposed sides, an air supply pipe communicating with one of the tubular end pieces, a coating material supply pipe communicating with the opposite tubular end piece, oppositely disposed nozzles mounted upon the sides of the frame and communicating with the respective tubular end pieces thereof so as to receive a continuous supply of air and coating material, and means for supporting the member to be coated between the nozzles.

5. A device for coating expanded metal and the like, including a frame formed with tubular end pieces, an air supply pipe communicating with and having a swiveled connection with one of the tubular end pieces, a coating material supply pipe communicating with and having a swiveled connection with the opposite tubular end pieces, the frame being adapted to be swung about its swiveled connections with the air supply pipe and coating material supply pipe, oppositely disposed nozzles carried by the frame and communicating with the tubular end pieces so as to receive a continuous supply of air and coating material, and means for supporting a member to be coated between the nozzles.

6. A device for coating expanded metal and the like, including a frame formed with tubular end pieces and connected by sides, the said sides being each formed with a pair of tubular members arranged side by side and communicating with the respective end pieces, a pair of tubular arms projecting from each side and communicating with the respective tubular members of the sides, oppositely disposed nozzles mounted between the tubular arms, an air supply pipe in communication with one of the tubular end pieces of the frame, a coating material supply pipe in communication with the opposite

tubular end piece of the frame, and means for supporting a member to be coated between the nozzles.

7. A device for coating expanded metal and the like, including a swinging frame formed with tubular end pieces connected by sides, each of the sides being composed of a pair of tubular members communicating with the respective end pieces, an air supply pipe communicating with and having a swiveled connection with one of the end pieces, a coating material supply pipe communicating with and having a swiveled connection with the opposite end piece, the frame being adapted to be tilted about its connections with the air supply pipe and

coating material supply pipe, a pair of tubular arms projecting from each of the side pieces of the frame and communicating with the respective tubular members thereof, nozzles mounted between the arms so as to receive a continuous supply of air and paint through the opposite tubular end pieces of the frame, and means for supporting a member to be coated between the nozzles. 25

In testimony whereof I hereunto affix my signature in the presence of two witnesses.
